REGENERATIVE OVEN

Josef Schaefer, Dortmund, Germany

Application December 31, 1930, Serial No. 505,674,
and in Germany February 10, 1930

2 Claims. (Cl. 263—19)

My invention relates to filling bodies for the regenerative chambers of regenerative coke ovens and similar ovens. These chambers have hitherto been filled with refractory bricks forming a chequerwork structure. In some cases, for instance where an individual regenerator compartment is allotted to each heating flue or to a number of heating flues, difficulties are encountered in the erection and removal of the chequerwork due to the presence of the partitions separating the individual regenerator compartments, because these partitions are difficult to erect in the narrow regenerator chambers and have to be removed and erected anew with every replacement of the chequerwork or other repair of the regenerators. Furthermore, the expansion due to heat causes cracks in these thin partitions invariably resulting in leakages. My invention has for its object to overcome these drawbacks.

To this end my invention provides as filling bodies for the regenerator chambers refractory cases which in their turn are filled with filling material, the cases being mounted in rows in the regenerator chambers.

Furthermore, because of the fact that the walls of these cases simultaneously may form the above-mentioned partitions of the individual regenerator compartments, any separate erection of such partitions may be dispensed with. As a consequence, the cases can be very conveniently built in and removed. I further arrange to mount the cases with lateral and vertical clearance in the regenerator compartments so that they are capable of expanding independently of the oven brickwork and even if they consist of several parts they are absolutely tight so that any leakage is prevented.

In order that my invention may be more readily understood, a preferred embodiment of the same is illustrated by way of example in the accompanying drawing in which

Figure 1 is a fragmentary vertical longitudinal section through a regenerator chamber filled with my new filling bodies.

Figure 2 is a corresponding fragmentary horizontal section, while

Figure 3 is a vertical transverse section through the regenerator of Figure 1.

Referring to the drawing, *a* denotes the regenerator chambers of a regenerative coke oven which chambers are filled each with one or more rows of refractory cases *g* which in their turn contain filling material *k* of any desired suitable type. The cases *g* have sufficient lateral

clearance relatively to the regenerator walls *w* that they are capable of expanding independently of these walls. In those oven designs where one or more heating flues *z* are allotted to one regenerator compartment, the cases *g* have a length 60 corresponding to the number of heating flues belonging to them, and the regenerator compartments formed by the cases may be fed in the usual manner alternatively with air or air and gas on the one hand and with waste heat on 65 the other hand. To establish the connection with the heating flues *z* of the oven the cases may be provided with connecting sockets *g*¹, as shown in Figure 3.

The width of the cases *g* may correspond to 70 that of the regenerator chamber or, as is likewise shown in Figure 3, to a portion thereof, according to the manner the individual regenerators are to be allotted to the heating flues. Furthermore, the cases *g* may be formed each by 75 one integral body or may be subdivided vertically, as shown, so that each case consists of a pile of superposed boxes which each contain filling bodies, the boxes in known manner engaging one another by tongue and groove joints. 80

What I claim as my invention is:—

1. A regenerative coke oven including regenerator chambers having side walls, of removable refractory cases mounted in said regenerator chamber, said refractory cases being in spaced 85 relation to the regenerator walls permitting independent expansion of the refractory cases, a plurality of superimposed boxes mounted in said refractory cases and filling bodies formed in each of said boxes. 90

2. A regenerative coke oven according to claim 1 wherein the walls of the cases form partitions for the regenerator chambers.

JOSEF SCHAEFER.
